U. S. WEDDINGTON

OIL GAS BURNER

Filed March 25, 1924

*U. S. Weddington,
Inventor*

*By Clarence A. O'Brien
Attorney*

UNITED STATES PATENT OFFICE.

ULYSSES S. WEDDINGTON, OF CHILDRESS, TEXAS.

OIL-GAS BURNER.

Application filed March 25, 1924. Serial No. 701,746.

To all whom it may concern:

Be it known that I, ULYSSES S. WEDDINGTON, a citizen of the United States, residing at Childress, in the county of Childress and State of Texas, have invented certain new and useful Improvements in Oil-Gas Burners, of which the following is a specification.

This invention relates to improvements 10 in fuel oil burners.

An object of the invention resides in providing a fuel oil burner, wherein the air supply is directed downwardly in an annular form, around a breaker plate 15 against which is projected an upwardly directed stream of fuel oil, under pressure, so that the air will readily vaporize the fuel leaving said breaker plate in the form of a substantially fine vapor, for subsequent 20 combustion.

Another object of the invention resides in providing a fuel oil burner, having an annular oil receiving cup, a central supply pipe extending through said cup for directing 25 a supply of fuel oil upwardly, under a substantial pressure for projecting it beyond the cup, to engage a breaker plate mounted above said cup and the ends of said feed pipe so that the breaker plate will cause 30 the stream of projected fuel oil to be broken up into finely divided form, in a direction downwardly toward said fuel cup, an air supply structure being provided over said fuel cup having an outlet around the breaker 35 plate, so that heated air will act on the finely divided fuel, for quickly vaporizing the same, for the purposes of combustion, the heat of combustion heating the air supply means, so that the same is preheated 40 before its contact with the vapors discharged from said breaker plate.

A further object of the invention is to provide a burner having an upwardly projected jet of fuel adapted to impinge against 45 the breaker plate and to be subsequently vaporized by air directed downwardly in concentric relation with the projected fuel for vaporizing the fuel discharged in finely divided form from said breaker plate for combustion, in order to produce complete combustion of the fuel oil, and an exceedingly hot flame.

The invention comprehends other objects 55 and improvements in the details of construction and arrangement of parts, which are more particularly described in the following

detailed description and in the claims, directed to a preferred form of the invention, it being understood, however, that variations may be made in the construction and arrangement of the parts without departing from the scope of the invention as described and claimed.

In the drawing, forming a part of this application:

The figure shows a vertical sectional view through a burner constructed according to the invention.

1 indicates the base of the burner which is of annular form and provided with an annular recess 2 on the under side thereof, the central portion having an annular depression 3 forming a trough 4 for excessive overflow of fuel from the outlet pipe, while the central portion is provided with a cup 5 and a pair of annular channels 6 arranged in concentric relation around the cup 5 and in stepped relation thereto. The central portion of the cup 5 is formed with a vertical opening for receiving the fuel feed pipe 7, the upper end of which projects slightly above the horizontal plane of the upper end of the cup 5, as clearly shown in the drawing, which pipe is adapted to project a rather small stream of fuel upwardly under a substantial force, for a purpose which will presently appear.

The base 1 is formed at diametrically opposite points with sleeve extensions 8 adapted to receive and mount the downturned ends of an air heating member 11, which is hollow in section, and the interior of which communicates with the recess 2 of the base, so that the supply of air is received through the recess 2, the tubular extension 8, and is directed upwardly to be heated in the horizontal portion 10 of the heating member for subsequent projection downwardly through the depending central outlet 11, which is of annular form, and of a size to overlie the outer annular channel 6, it being arranged in spaced relation above said channel. A rod 12 is mounted in the upper wall of the heating member 9, and depends in the central portion in axial relation with the depending air outlet 11, for supporting the breaker plate 13, in horizontal concentric relation slightly above the lower end of the outlet 11, and directly above the fuel feed pipe 7. The breaker plate is arranged so that the heated air being discharged therefrom will be directed downwardly in an an-

nular path, against the annular channel 6, for vaporizing any liquid fuel contained therein.

In the use of a burner of this type, priming fuel is placed in the cup 5 and the annular channels 6 for heating the air heating member 9, so that the air for the combustion of the fuel oil will be reheated. In the normal operation of the burner, the fuel oil is projected from the relatively small fuel feed pipe 7 upwardly against the central portion of the breaker plate 13, so that said plate will break the stream of fuel into a finely divided form, discharging it outwardly in all directions, and downwardly toward the annular channel 6 and the cup 5, the downward blast of heated air around said breaker plate contacting with the finely divided fuel, and effectively vaporizing the same before it reaches the channels 6, in the cup 5, and also vaporizing any fuel in said channels, and cups, combustion taking place immediately upon the mixture of the air with the finely divided fuel which will produce complete combustion of the fuel oil, and an exceedingly hot flame, which will superheat the air heating member 9, so that all of the air passing therethrough under the normal operation of the burner will be superheated for more readily vaporizing and aiding in the combustion of the fuel oil.

From the foregoing description, it will be clear that a fuel oil burner has been provided which is adapted for use in furnaces, stoves or the like, or in any other form of apparatus where such a burner is useful which would utilize a relative small quantity of fuel oil, adapted to be mixed with a sufficient quantity of air to insure the complete combustion thereof, and to form a hot flame, and at the same time reduce the likelihood of the formation of carbon in any quantity.

What is claimed is:

1. An oil gas burner comprising a base provided with air discharge openings and

provided at its center with an oil receiving cup, an air supplying and heating duct disposed over said base and having downturned ends connected to said discharge opening, said duct being formed with an air outlet disposed over said cup, a discular oil breaker plate disposed in said outlet and spaced therefrom to provide an annular passage for the discharging air, said plate being spaced above the edge of said outlet, and an oil feed pipe extending through said cup and terminating beneath said plate, said pipe being adapted to project oil under pressure against the under side of said plate to be vaporized and fixed with the discharging and heated air, whereby to form a combustible gaseous mixture.

2. An oil gas burner comprising a substantially annular base provided with air escape necks at diametrically opposite points and provided with a central depression simultaneously forming an overflow trough and a central projection, the top of said projection being formed with radially spaced annular grooves and with a central depression forming an oil receiving cup, an air heating duct disposed above said base and having down turned ends connected with the aforesaid escape necks, said duct being formed with a depending tubular air discharge disposed over the aforesaid projection, one of the aforesaid grooves being disposed beyond said discharge, a discular breaker plate arranged within said air discharge and having its peripheral edge spaced from the wall of said discharge to provide an annular and restricted air passage, said plate being disposed above the edge of said discharge, and a fuel feed pipe extending upwardly through the aforesaid cup and terminating in spaced relation below the under side of said plate.

In testimony whereof I affix my signature.

ULYSSES S. WEDDINGTON.
